UNITED STATES PATENT OFFICE.

EDWARD ROSENBERG, OF BROOKLYN, NEW YORK.

LOCK FOR POCKETS.

1,230,520.

Specification of Letters Patent.

Patented June 19, 1917.

Application filed February 11, 1916. Serial No. 77,697.

To all whom it may concern:

Be it known that I, EDWARD ROSENBERG, a citizen of the United States, and a resident of New York, borough of Brooklyn, 5 county of Kings; and State of New York, have invented certain new and useful Improvements in a Lock for Pockets, of which the following is a full, clear, and exact specification.

10 This invention relates more particularly to a class of safety devices adapted to be used in conjunction with the pockets of garments.

My invention has for its object primarily 15 to provide a lock adapted to be applied to the pocket especially of a garment whereby the pocket may be locked against being accidentally, or surreptitiously opened when containing a watch, or other valuables, and 20 which is formed so as to be easily operated when desired. This is accomplished mainly by providing an apertured keeper adapted to be fastened on the inner wall of the pocket of a garment so as to be disposed in 25 an opening therein. Adapted to be applied to an opposed part of the outer wall of the pocket is a hasp member of less size than the aperture of the keeper, and which is pivoted eccentrically with relation to the center 30 of the aperture so as to be swung in the radius of a circle for passage therethrough and then reversely swung on the keeper to confine it between the hasp member and the outer wall of the pocket whereby the pocket 35 will be locked against being accidentally and surreptitiously opened.

A further object of the invention is to 40 provide a lock for pockets of a simple and efficient construction, and which is susceptible of being made in any desired shape and size.

A practical embodiment of the invention is represented in the accompanying drawing forming a part of this specification in 45 which similar characters of reference indicate corresponding parts in all the views, the said invention being more fully described hereinafter, and then pointed out in the claim at the end of the description.

50 In the drawing, Figure 1 is a fragmentary view showing part of a garment with one form of lock embodying my invention applied thereto.

Fig. 2 is an enlarged fragmentary sectional view taken on the line II-II of 55 Fig. 1.

Fig. 3 is a rear view of the device when assembled, looking in the direction of the arrow III of Fig. 2.

Fig. 4 is a front view of the device when 60 assembled, looking in the direction of the arrow IIII of Fig. 2.

Fig. 5 is a front view of the keeper used in the device, and

Fig. 6 is a front view of the hasp em- 65 plied in the device.

The device, or lock has a keeper 10 which is preferably in the form of a plate 11 having in one of its faces a recess 12, and through the plate centrally of the recess is 70 an aperture 13. While the plate 11 is illustrated as being circular it may be of any suitable shape and size, and while the aperture is shown as being substantially triangular it may be otherwise formed as occasion requires. When the lock is applied to the pocket 14 of a garment, as 15, the keeper 10 is positioned on the inner wall 16 of the pocket so that its recessed portion will be disposed in an opening 17 provided in the 80 inner wall of the pocket and passing entirely through the coat or vest whereby access may be had to the interior of the pocket from the interior of the garment. The aperture 13 will then be in opposition to the 85 outer wall 18 of the pocket, and the plate 11 of the keeper may be fastened to the garment by stitches, or other means passed through holes, as 19, formed at spaced intervals through the plate as well as through 90 the inner wall of the pocket.

Serving to coöperate with the keeper 10 for permitting the pocket to be releasably locked, a hasp member, as 20, is provided. The hasp member 20 is composed of a supporting plate 21 which is preferably similar in shape and size to the plate 11 of the keeper 10, and this supporting plate is fastened by stitches, or other means passed through spaced holes 22 in the plate to the 100 inner surface of the outer wall 18 of the pocket so as to be in opposed relation with the plate 11 of the keeper. Projecting from the supporting plate 21 toward the plate 11 is a pin 23 disposed eccentrically with 105 respect to the center of the angular aperture 13 of the plate of the keeper 10, and this pin is of a length whereby it will extend some distance beyond the plate 11 when guided through the angular aperture 110 of the keeper. Rotatable on the free end of the pin 23 is a latch, or swinging arm 24

of a triangular form to correspond to the shape of the aperture 13 of the keeper, but this angular latch is slightly smaller than the aperture. As shown, one of the angular ends of the latch 24 is pivoted on the pin 23 to allow the latch to be swung in the radius of a circle to alinement with the aperture 13 of the keeper for being guided therethrough, and to permit the latch to be manually swung projecting from the exposed face of the latch may be a knob, or handle 25.

In order to lock together the parts of the latch when applied to the pocket of a garment, as above explained, the outer wall of the pocket is moved toward its inner wall, and when the latch, or hasp 24 is swung on its pivot on alinement with the aperture 13 of the plate 11 the latch is guided through the aperture. By then reversely swinging the latch it will be disposed on the keeper to confine it between the supporting plate 21 and the latch. The pocket will thereby be locked against being accidentally, or surreptitiously opened when containing a watch, or other valuables, and by similarly operating the parts of the device for allowing the latch 24 to be withdrawn through the aperture 13 of the plate 11 of the keeper the pocket may be opened to gain access thereto.

In the foregoing description, I have embodied the preferred form of my invention, but I do not wish to be understood as limiting myself thereto, as I am aware that modifications may be made therein without

departing from the principle, or sacrificing any of the advantages of this invention, therefore I reverse to myself the right to make such changes as fairly fall within the scope thereof.

Having thus described my invention, I claim as new and desire to secure by Letters Patent:—

A lock comprising a circular plate having a centrally disposed circular recess provided therein, and having a triangular aperture centrally of the recess, the marginal flange of said plate being provided with a series of perforations whereby said plate may be attached to an object, a second plate provided with a series of perforations in its outer edge whereby it may be attached to a second object opposed to said first mentioned object, a pin projecting from the second plate and located adjacent one corner of the first mentioned plate, said pin being adapted to pass through the aperture in the first mentioned plate and disposed eccentrically thereto, and a triangular arm eccentrically and rotatably mounted on the pin and adapted to pass through the aperture in the first mentioned plate and then to be swung on the pin to confine the first plate between the arm and the second plate, substantially as described.

This specification signed and witnessed this 9th day of February A. D. 1916.

EDWARD ROSENBERG.
